CLAIM

The ornamental design for an air dehydrating breather as shown and described.

DESCRIPTION

FIG. 1 is a front perspective view of an air dehydrating breather showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear perspective view thereof.

The dashed broken lines in the drawing depict portions of the air dehydrating breather that form no part of the claimed design.
